US00D603352S

(12) **United States Design Patent**
Panaccione et al.

(10) **Patent No.:** **US D603,352 S**
(45) **Date of Patent:** ** *Nov. 3, 2009

(54) **LED PACKAGE**

(75) Inventors: **Paul Panaccione**, Newburyport, MA (US); **Christian Hoepfner**, North Andover, MA (US); **Georgia Chmielewski**, Plaistow, NH (US); **John W. Graff**, Swampscott, MA (US); **Robert F. Karlicek**, Chelmsford, MA (US); **Daniel Mendoza**, Pelham, NH (US); **Michael Denninger**, Belmont, MA (US)

(73) Assignee: **Luminus Devices, Inc.**, Billerica, MA (US)

(*) Notice: This patent is subject to a terminal disclaimer.

(**) Term: **14 Years**

(21) Appl. No.: **29/285,430**

(22) Filed: **Mar. 29, 2007**

(51) LOC (9) Cl. **13-03**

(52) U.S. Cl. **D13/180**

(58) Field of Classification Search **D13/179, D13/180, 182; D26/2; 257/79, 80, 81, 88, 257/89, 95, 98, 99, 100; 313/483, 498, 500; 362/555, 800; 165/80.3; 174/254, 255**

See application file for complete search history.
